PUMPING APPARATUS

Loren W. O'Kelley, Porterville, Calif.

Application November 30, 1949; Serial No. 130,241

1. Claim:

(Cl. 103—5) A pumping apparatus, including a base, a main pump unit mounted on the base, a conventional hand pump assembly mounted on the base, a horizontally elongated housing mounted on the base, a transverse filter screen disposed in an inclined position in the housing, and a duct connected to the main pump unit and the hand pump assembly, the duct communicating with the housing.

This invention relates to new and useful improvements and structural refinements in pumping apparatus, more particularly, pumping units such as commonly employed in garden or field sprinkling systems; and the principal object of the invention is to substantially minimize, if not altogether prevent, any possibility of the pumps becoming obstructed by sand, gravel, etc., thus rendering the entire sprinkler system ineffective.

In particular, the invention concerns itself with pumping units employing a main pump for drawing water out of a well and a secondary or "booster" pump for increasing the pressure of water drawn by the main pump, the invention being directed to the provision of filtering means for preventing obstruction of the booster pump which, unlike the main pump, is more susceptible to becoming clogged by foreign matter as above stated.

Some of the advantages of the invention reside in its simplicity of construction, in its efficient and trouble-free operation, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a side elevational view of the invention, the same being partially broken away so as to reveal its construction;

Figure 2 is a cross sectional view, taken substantially in the plane of the line 2—2 in Figure 1, and,

Figure 3 is a cross sectional view, taken substantially in the plane of the line 3—3 in Figure 1.

Like characters of reference are employed to designate like parts in the specification and throughout the several views.

Referring now to the accompanying drawings in detail, the invention is embodied in a pumping apparatus designated generally by the reference numeral 10, the same being mounted upon a suitable base 12 and consisting, in accordance with conventional practice, of a main pump 14 communicating through the medium of a pipe 16 with a well, a suitable "foot valve" 18 being provided in the pipe 16 between the well and the pump 14, as is customary.

The main pump 14 includes a housing 20 and a rotatable impeller 22 mounted directly upon the armature shaft 24 of an electric motor 26 which, in turn, is supported by the base 12, as shown.

The water drawn by the pump 14 is delivered through a duct 28 and a conventional hand pump assembly 30 may be provided on this duct for the purpose of "priming" the pump 14.

A horizontally elongated housing 32 is also mounted on the base 12 and a transverse filter screen 34 is disposed in an inclined position in this housing, which may be achieved by providing the inner walls of the housing with suitable beads or cleats 36.

The screen 34 has what for purposes of orientation may be described as an upper surface 38 and a lower surface 40, and the screen separates the housing 32 into a sediment chamber 42 and a transfer chamber 44, which chambers are disposed at the respective upper and lower sides or surfaces of the screen, as will be clearly apparent from Figure 1.

The transfer chamber 44 of the housing 32 is extended so as to afford what may be called a bay 46 accommodating a rotatable impeller 48 of a booster pump, the impeller 48 being secured to a shaft 50 which extends outwardly from the housing 32 into a gear case 52 and is driven at a relatively higher speed from the armature 24 of the motor 26 through the medium of step-up gearing 54 so that water delivered by the main pump 14 into the housing 32 (as will be herein-after described) may be "boosted" in pressure by the impeller 48. As will be observed, the aforementioned gear case 52 is also mounted on the base 12, and the outlet duct or pipe of the booster pump is indicated at 56 as communicating with the extension or bay 46 of the housing chamber 44.

The aforementioned duct 28 from the main pump 14 communicates with the chamber 42 at a point adjacent the upper edge of the screen 34, so that water delivered by the pump 14 will be discharged onto the screen and will promptly pass through it, while sand, gravel, etc., in the water will remain in the sediment chamber 42, thus protecting the booster impeller 48 against obstruction or damage.

The sediment in the chamber 42 may be occasionally drained through the medium of an outlet pipe 58 and suitable shut-off valves 60, 62 and 64 may be provided on the respective pipes 28, 56 and 58 for obvious reasons. Moreover, a pressure gauge 66 may be provided on the pipe 56, as shown.

Finally, a transparent inspection window 68 may be provided on the chamber 42 of the housing 32, this window being located directly opposite the screen 34 so that the screen may be inspected at frequent intervals for any effect of

clogging or obstruction without the necessity of dismantling the housing 32.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

In a pumping apparatus, the combination of a housing, a transverse filter screen provided in said housing and separating the same into a sediment chamber and a transfer chamber, a primary pump including an outlet duct connected to said sediment chamber, a discharge duct extending from said transfer chamber, a secondary pump provided in the transfer chamber adjacent said discharge duct, and common means for actuating said primary and secondary pumps, said common means including a prime mover having a rotatable drive shaft connected at one end to said primary pump, the other end

of said shaft having a first gear secured thereto for rotation therewith, an offset second shaft having a second gear and said secondary pump secured thereto for rotation therewith, said first and second gears having a preselected gear ratio and being interengaged for driving said secondary pump at a speed different from that of said primary pump.

LOREN W. O'KELLEY.
